MANIFOLDING BOOK

Arthur H. Phillips, Hempstead, and William Allan, Jr., New York, N. Y., assignors to American Sales Book Company, Limited, Toronto, Canada, a corporation of Ontario

Application October 14, 1924, Serial No. 743,533

4 Claims. (Cl. 282—12)

This invention relates to manifolding books which are intended to supply a plurality of sets of printed forms successively in writing position.

An object of this invention is to provide a device 5 of the character described in which the forms are held in registry with each other in a new and improved manner and in which sheets are adapted to lie intimately in contact to insure clear inscription.

10 A further object is to provide a pad formed of a plurality of strips interfolded zigzag to form superposed sets of superposed leaves in which the leaves of each set are attached together in such a manner as to facilitate the folding and 15 unfolding of the strips together to maintain the forms in registry.

10 A further object of this invention is to provide a pad of the character described in which the various forms may be attached together in 20 such a manner as to facilitate their handling throughout an auditing routine, but to permit their easy detachment from each other when desired without tearing the sheets.

Other objects will in part be obvious and will in 25 part appear hereinafter.

The invention accordingly comprises the features of construction, combinations of elements, and arrangement of parts, which will be exemplified in the construction hereinafter set forth and 30 the scope of the application of which will be indicated in the claims.

For a fuller understanding of the nature and objects of the invention reference should be had to the following detailed description taken in 35 connection with the accompanying drawing, in which:

Figure 1 is a perspective view of a pad embodying this invention, the successive layers of the compound strip being separated, more clearly to 40 show the construction;

Fig. 2 is an end view of the compound strip as shown in Fig. 1;

Fig. 3 is a modification of the invention; and Fig. 4 is an end view of the modification.

45 It has heretofore been proposed to construct manifolding pads by folding a strip of paper zigzag by lengthwise folds and thereafter folding the compound strip so formed zigzag by cross folds to form superposed sets of 50 superposed record leaves. Such pads have not, however, proven satisfactory for many purposes, partly by reason of the fact that the different strips constituting the compound strip are integral with each other at the folded edges and do 55 not satisfactorily yield to each other as the com-

pound strip is folded and unfolded. Furthermore, by reason of the fact that the strip is completely closed upon one side and the strips are mechanically separated in operation, to insert between them the transfer material, air pockets are apt to 60 form between the sheets which cushion type used upon the sheets and thus have a tendency to prevent the writing from being clear on all the copies.

Moreover where a number of copies of a single 65 sales record are required, it is desirable that the different copies be upon different colored paper to distinguish the one from the other in the different uses to which the several copies are put, and it is frequently desirable to have the original 70 upon a good grade of paper and the copies upon a cheaper grade. All this is obviously impractical where all of the forms are made from the same original sheet.

To overcome this objection, it has heretofore 75 also been proposed to superpose a plurality of strips which may thus be of different colored paper and to attach them together at the edge by a continuous line of paste. Such pads have, however, proved unsatisfactory by reason of the fact 80 that the firm attachment at the edge makes severance of the sheets in a neat and convenient manner unsatisfactory, if not impossible, and moreover the continuous line of paste interferes with the folding of the compound sheet more even 85 than the integral connection between the strips at their edge, and it is more impervious to the passage of air.

All such forms of pads, moreover, are ill 90 adapted for use with many manifolding machines which employ mechanism for separating the various forms of a set from each other as they are fed on to the tablet by reason of the fact that the sheets are so firmly attached that it is difficult to sever them uniformly without tearing them. 95

In accordance with this invention, it has been discovered that the foregoing difficulties can be overcome by superposing a plurality of strips having corresponding forms printed thereon and attaching the strips together at spots spaced apart 100 along one edge of the strip.

In the form of the invention illustrated in Fig. 1, the pad is composed of a plurality of strips 1, 2, 3, 4, 5 and 6, each of which independently of the others, may be of any color, weight or quality of 105 paper desired, and each of which may have upon it a suitable record form for the reception of inscriptions. These strips are superposed to form a compound record assembly or record strip and the superposed sheets of each set are attached 110

together in pairs at opposite sides of the assembly. These attachments are at alternate sides of the compound strip, that is; strips 1 and 2 comprising the first pair are attached at the front edge as seen in Fig. 1, and strips 2 and 3 comprising the second or next adjacent pair are attached at the rear edge of the assembly as best seen in Fig. 2. The attachments as herein shown are in the form of small spots of adhesive at longitudinally spaced intervals along the opposite longitudinal assembly edges. According to the present embodiment single spots of adhesive are employed longitudinally spaced apart by the length of the record forms or leaves interposed between adjacent successive severance lines 6a, and positioned respectively directly at the lines of severance 6a, between the forms. It will be noticed also that the adjacent strips or leaves of each pair are free from attachment with each other at all points thereof positioned transversely of the assembly from the respective adhesive attaching spots, thus providing for free insertion of additional sheets or strips in superposed manifolding relation between the adjacent strips of each pair; for example carbon strips may be thus inserted. In the illustrative embodiments of the invention shown, it will be noticed that the transverse severance lines 6a are respectively positioned between adjacent successive blank forms or writing areas upon which the inscriptions are written. Also as is herein shown these attaching adhesive spots are positioned only at points intermediate the adjacent writing areas, the strips being free from attachment with each other at the writing areas.

With this construction, when a plurality of forms are removed from the compound strip, the severed forms are attached at both top and bottom, the line of severance having passed midway through the spot of attachment. Thus, the next set of forms as they are fed to the machine are held in registry by the portion of the point of attachment which remains, while the set of forms severed from the machine are held together by the points of attachment into a zigzag or "fan-fold" form.

It is desirable that there shall be employed in making the attachment between the sheets, an adhesive capable of retaining the sheets together through the machine, but permitting them to be severed at the adhesive without tearing the sheets. For this reason the commercial pastes have been found in this respect preferable to glues.

The form of the invention illustrated in Fig. 3 is similar to that illustrated in Fig. 1, save that the sheets comprising strips 11, 12 and 13 are all attached together at the same side instead of the pairs being attached at opposite sides as in Fig. 1. These attachments are illustrated as being on one side of the compound strip and with this form, also, it is preferred to place the points of attachment at the lines of severance for the reasons previously given. It will of course be understood that these lines of severance extend transversely of the respective record strips similarly to the severance lines 6a of Fig. 1 as fully set forth above. With this form of invention, it will be obvious that when a set of forms is removed from the machine, it will be in the form of a book of leaves all opening from the same side.

In either modification however if the attachment of the sheets is to be at the front or rear edges of the sheets instead of the lateral then the points of attachment should be behind or in advance of the line of severance. For some purposes moreover, where it will not be necessary to

attach every set of forms, points of attachment may be spaced greater distances apart.

With the above constructions, it has been found that the compound strip will fold into and out of zigzag formation without buckling and without material longitudinal displacement of the forms. Moreover, by reason of the fact that it is possible for the air beneath any particular form to escape upon all four sides, the forms can be readily made to lie flat upon each other to insure distinct copies.

The above constructions, moreover, while more efficient and satisfactory in operation than pads having continuous line of paste along one edge, are in fact also simpler and cheaper to construct, being capable of manufacture with machinery of a less complicated nature and less liable to get out of order.

Since certain changes may be made in the above construction and different embodiments of the invention could be made without departing from the scope thereof, it is intended that all matter contained in the above description or shown in the accompanying drawing shall be interpreted as illustrative and not in a limiting sense.

Having described our invention, what we claim as new and desire to secure by Letters Patent, is:

1. A manifolding assembly including in combination, a traveller strip having writing areas spaced therealong, a second traveller strip in superposed relation with said first mentioned strip and having attachment with the latter at a series of longitudinally spaced points positioned between said writing areas, said first and second traveller strips being free from each other at the writing areas, said traveller strips each having a plurality of longitudinally spaced, transverse, weakened severance lines respectively positioned between adjacent writing areas, and each of said severance lines extending intermediate the forward and rearward parts of the corresponding attachment between the strips whereby each of said attachments continues to attach the strips together both forwardly and rearwardly of the respective severance line after strip severance along said line.

2. A manifolding assembly including in combination, a traveller strip having writing areas spaced therealong, a second traveller strip in superposed relation with said first mentioned strip and having attachment with the latter at a series of longitudinally spaced points positioned between said writing areas, said first and second traveller strips being free from each other at the writing areas, said attachments including adhesive spots between the first and second strips, said traveller strips each having a plurality of longitudinally spaced, transverse, weakened severance lines respectively positioned between adjacent writing areas, each of said severance lines extending intermediate the forward and rearward parts of the corresponding adhesive spot, whereby the latter continues to attach the strips together both forwardly and rearwardly of the respective severance line after strip severance along said line, said attachments being confined to spots along one longitudinal edge of the assembly while said strips are free from attachment with each other along the opposite longitudinal edge of the assembly.

3. A manifolding assembly including, in combination, a plurality of traveler strips superposed with each other and having transverse division lines dividing them to form a plurality of sets of superposed leaves, an adjacent pair of said

strips having attachment with each other at a series of points spaced apart longitudinally of the strips a material distance leaving intermediate greatly elongated strip portions unattached, so as to avoid buckling upon folding or unfolding, said attachments being confined to positions along the longitudinal edges of the attached strips, said pair of attached strips being free from attachment with each other at all points thereof positioned transversely of the strips from the attached edges, and a pair of adjacent strips next to said first mentioned pair having attachment with each other at a series of points also spaced apart longitudinally of the strips a material distance leaving intermediate greatly elongated strip portions unattached so as to avoid buckling, said last mentioned attachments being positioned at the opposite longitudinal edge of the assembly from said first mentioned series of attachments, said last mentioned adjacent strips being free from attachment with each other at points thereof transversely of the strips from the last mentioned attached edges, said division lines being in the form of transverse weakened severance lines extending intermediate the forward and rearward parts of the corresponding said attachments between the strips whereby each of said attachments continues to attach the strips together both forwardly and rearwardly of the respective weakened severance lines after strip severance along said lines.

4. A manifolding assembly including, in combination, a pair of traveler strips superposed with each other and interfolded in zigzag relation to form a plurality of sets of superposed record leaves, each of said strips having writing areas spaced in series therealong, at least two adjacent strips of the assembly having attachment with each other at a series of points spaced apart longitudinally of the strips and positioned respectively intermediate adjacent writing areas, each of said series of attaching points being confined to a position along one longitudinal edge of the two adjacent attached strips, and said strips at said longitudinal edge being free from attachment with each other at greatly elongated stretches between said attachments so as to avoid buckling upon folding or unfolding, the opposite longitudinal edges of these two strips and all parts thereof intermediate their longitudinal edges being free from attachment with each other, each of said strips having longitudinally spaced transverse weakened severance lines arranged therealong and each extending intermediate the forward and rearward parts of the corresponding said attachments between the strips whereby each of said attachments continues to attach the strips together both forwardly and rearwardly of the respective weakened severance lines after strip severance along said lines.
